UNITED STATES PATENT OFFICE.

CHARLES B. ROBERTSON, OF COLUMBUS, OHIO, ASSIGNOR OF ONE-HALF TO
O. J. DEVANEY, OF COLUMBUS, OHIO.

PNEUMATIC MATTRESS.

1,285,391.

Specification of Letters Patent Patented Nov. 19, 1918.

Application filed May 27, 1918. Serial No. 236,664.

To all whom it may concern:

Be it known that I, CHARLES B. ROBERTSON, a citizen of the United State, residing at Columbus, in the county of Franklin and

5 State of Ohio, have invented certain new and useful Improvements in Pneumatic Mattresses, of which the following is a specification.

This invention relates to pneumatic mattresses, and has for its object to provide a comfortable and efficient mattress of such construction as to be capable of being folded into a relatively compact condition when not in use in order to be readily transported, or 10 when adapted for active service to be correspondingly easy and convenient to inflate to a proper degree of buoyancy and resiliency, whereby the same may be employed in the same capacities and with the same comforts of ordinary mattresses.

Another object of the invention is to produce a mattress particularly adapted for the needs of soldiers, campers, and others who desire a mattress which may be instantly set 15 up for comfortable usage irrespective of adverse conditions or localities, and yet may be folded when not in service to assume a bundle of minimum bulk with accompanying lightness in weight, so that the same 20 may be conveniently carried or otherwise transported from place to place.

A further object of the invention resides in a mattress capable of being employed with the same degree of comfort and utility 25 as is accomplished through the use of an ordinary stuffed or hair mattress, and one which will possess and maintain a high standard of buoyancy or resiliency throughout its life regardless of hard or wear 30 parting usage; the same further including features of construction which will render it perfectly sanitary, easy to keep in a cleanly condition, and capable of convenient repair in the event of damage to one or more of its 35 several members.

To this end, the invention consists of a pneumatic mattress constructed to include an outer fabric covering in which is positioned a plurality of parallel extending in- 40 flatable tubes, means being provided to maintain said tubes in spaced relation, so that

when inflated the same will assume a proper cross sectional formation in order to preserve the desirable, substantially flat surfaces characteristic of stuffed mattresses.

The invention further includes a novel form of valve mechanism for use in connection with the inflatable tubes, whereby the latter will be capable of being simultaneously inflated or deflated and, furthermore, 60 in the event of one or more of said tubes becoming accidentally deflated, said valve mechanism will automatically act to localize the leakage of air and to prevent the same from affecting the inflated condition of the 65 undamaged tubes.

A still further object is to provide the end of the covering with an entrance opening, which latter being protected through the agency of overlapping flap members, this 70 entrance opening serving to permit of the removal or insertion of the tube members within the covering, and the flap members, in turn, serving to preserve the desired contour of the mattress, and to brace and conceal the internal parts thereof.

With these and other objects in view, as will appear as the description proceeds, the invention accordingly consists in the novel features of construction, combination of elements, and arrangement of parts herein-after fully described and having the scope thereof particularly set forth in the appended claims.

In the drawing, forming a part of this specification, and in which similar characters of reference denote corresponding and like parts throughout the several views thereof:

Figure 1 is a plan view of my improved mattress, one end thereof being partly broken away and shown in section to disclose the underlying structure.

Fig. 2 is a vertical longitudinal sectional view taken along the line 2—2 of Fig. 1,

Fig. 3 is a transverse sectional view taken along the line 3—3 of Fig. 1,

Fig. 4 is a detail horizontal sectional view disclosing more particularly the inlet and exhaust manifolds, and illustrating their associated valve mechanism, 100

Fig. 5 is an end view of the mattress and

disclosing the outer flaps in an open position in order to set forth the laced inner flaps and the co-operative manifolds.

Fig. 6 is a fragmentary end elevation of 5 the mattress disclosing a slightly modified form of the head end thereof.

Referring more particularly to the details of the invention, the mattress 1 comprising the preferred form of the invention, consists 10 of an outer fabric covering 2, preferably of stout canvas or the like, the same being stitched or otherwise reinforced along its marginal edges 3 to assist in defining the proper contour thereof when inflated. One 15 end of the covering is permanently closed by means of a fixed end member 4, while the opposite or lower end 5 is left open, so that access may be obtained with regard to its interior construction.

20 In this instance the interior of the covering or casing 2 is provided with longitudinally extending, flexible, divisional walls 6, which have their edges preferably secured in any suitable permanent manner to the adjacent 25 surfaces of the covering, and these walls 6 serve to define a plurality of parallel disposed, tube receiving compartments 7. The latter have their upper ends closed by means of the end member 4, and their lower ends 30 in this instance, are left open to permit of the reception of a plurality of inflatable tubes 8 therein. These tubes are preferably formed from soft rubber or the like, so that when inflated the same will impart to the 35 mattress a proper degree of resiliency, and consequent desirable comfort affording properties. It will be manifest that through the agency of the walls 6, and by providing the mattress with a plurality of the tubes 8, 40 the desired rectilineal contour of the mattress will be preserved when the same is inflated, thus preventing undue bulging or distention of certain parts thereof, but on the other hand positively serving to retain 45 the same equally resilient at all positions over its entire area. In other words, the mattress will possess the same resilient properties, when weight is imposed thereon, along positions adjacent to its sides as well as in 50 its central portion, or vice versa.

In order to inflate or deflate the tubes 8, there is provided a flexible air inlet manifold 9, which in its preferred form consists of a section of rubber tubing disposed to extend 55 in this instance transversely of the mattress 1, and contiguous to the open end thereof. This manifold is provided with a plurality of spaced inwardly extending tubular offsets 10, the latter terminating within the 60 tubes 8, whereby air passing through the manifold 9 will be discharged uniformly into said tubes. This manifold is further provided with an inlet tube 11, to which any suitable form of pump, bellows or other air 65 compressing device (not shown) may be at-

tached in order to inflate the tubes 8, or if desired the tubes 8 may be inflated manually.

The offsets 10 of the manifold 9 are preferably equipped with ball valves 12, which operate between reduced valve seats 13 and stop pins 14, this construction permits air admitted into the tubes to be automatically retained therein, as the ball valves are so constructed to firmly seat when subjected to the influence of the air pressure afforded by 75 the tubes 8, so as to prevent undue escape of air from said tubes. The valves 12 are preferably formed from rubber, in order to be of a non-corroding nature and to be capable of firmly engaging with their respective 80 seats 13 to eliminate undue air leakage.

To exhaust air from said tubes, there is provided an exhaust manifold 15, which is similar in construction to the manifold 9, being preferably formed from a suitable flexible material and is provided with communicating tubular offsets 16, the latter being situated contiguous to the offsets 10 and like the latter are disposed to enter the tubes 8. This latter manifold 15 is centrally provided with a cap covered vent member 17, through which air from said exhaust manifold is discharged. The offsets 16 in this instance are provided with ball valves 18, which act in opposition to the valve 12. 90 These valves 18 are forced by air pressure within the tubes 8 away from their seats 19 to leave the latter normally uncovered, whereby upon the removal of the cap covering the vent member 17, air will be permitted 100 to exhaust from the tubes 8, and through the manifold 15 to deflate the mattress. However, in the event of one of the tubes 8, or more, becoming damaged or punctured in such manner as to accidentally permit of the 105 undue escape of air therefrom, the valves 18 will respond to the back pressure contained in the manifold 15 so as to force the valve 18 of the damaged tube into engagement with its seat 19, thus permitting of only the 110 damaged tube to become deflated, and without in any way disturbing the inflated condition of the remaining tubes. Thus, it will be manifest, means have been provided for localizing the effects of a damaged tube, 115 without permitting the remaining tubes to be influenced thereby. The offsets 10 and 16 are maintained in engagement with their respective tubes through the agency of a cemented strip or the like 20, which engages 120 with the flanges 21 of the offsets and securely retains the latter in close engagement with said tubes thereby providing a substantially fluid tight joint.

The open end 5 of the covering is provided with a plurality of inwardly situated spaced flaps 22, which latter have certain of their longitudinal edges sewed or otherwise secured as at 23 to said covering, thus leaving their free adjacent edges slightly sep- 130

arated, and through this space, defined by said free edges, the inlet and exhaust manifold 9 and 15, respectively, extend. The adjacent edges of the flaps 22 are preferably laced together as at 24, and from this it will be noticed that said flaps will serve to define an end wall for the lower ends of the tubes 8, thus preventing the latter from becoming unduly distended at their lower ends, 10 at the same time serving to maintain the desired contour or formation of the mattress. To protect the manifolds 9 and 15 and to conceal the latter from view, I may provide additional flaps 23' and 24', the former being capable of being folded to protect the side edges of the mattress and the latter serving to incase and guard the manifolds. Any suitable means may be provided to retain the flaps 23 and 24 in their folded 15 position, yet to permit the same to be readily folded to assume out of the way positions and to thus render the interior of the mattress quickly and conveniently accessible.

From the foregoing it will be evident that 25 there is provided mechanism whereby the objects of the invention have been achieved, and that all of the desirable features of construction and operation above mentioned are, among others, present. The mattress is capable of being readily inflated or deflated as desired and it is of such construction that when deflated the same may be conveniently folded to assume a bundle of relatively small proportions, so that the same may be easily 30 carried or stored away in but a minimum of storage space. This feature of construction particularly renders the mattress adaptable to the needs of soldiers, campers and others requiring a mattress of this character, which also must be capable of being 35 conveniently transportable. Another possible use of the mattress is in connection with sea going vessels, since if the latter should meet with disaster, the mattress may be employed in the capacity of a life preserver or raft, as a raft of practicable proportions may be quickly formed by lashing together 40 a plurality of said mattresses, this being accomplished by passing a cable through the 45 eyelets 26 provided for that purpose. As

shown in Fig. 6, the head of the mattress may be enlarged as at 27 in order to eliminate the use of a pillow or the like.

I claim:

1. In a pneumatic mattress, the combination with a plurality of inflated tubes, of valve mechanism for governing the admission and expulsion of air into and from said tubes, comprising independent flexible inlet and exhaust manifolds disposed to be in communication with the interior of said tubes, check valves carried by said inlet manifold and automatically operable to permit of an inflow of air into said tubes under pressure and constructed to automatically seat upon release of said pressure to retain the air within said tubes, and similar check valves carried by said exhaust manifold and operable upon an undue leakage of air from any one of said tubes to localize the escape of air therefrom and to prevent said leakage from affecting the inflated condition of the remaining tubes.

2. In a pneumatic mattress, the combination with a plurality of inflated tubes, of valve mechanism for governing the admission and expulsion of air into and from said tubes, comprising independent flexible inlet and exhaust manifolds disposed to be in communication with the interior of said tubes, check valves carried by said inlet manifold and automatically operable to permit of an inflow of air into said tubes under pressure and constructed to automatically seat upon release of said pressure to retain the air within said tubes, similar check valves carried by said exhaust manifold and operable upon an undue leakage of air from any one of said tubes to localize the escape of air therefrom and to prevent said leakage from affecting the inflated condition of the remaining tubes, laced end flaps carried by said members and serving as an end wall for said tubes and between the spaced edges of which flaps the manifolds outwardly protrude, and a plurality of concealing flaps arranged to overlie said former flaps to protect and incase said manifolds.

In testimony whereof I affix my signature.

CHARLES B. ROBERTSON.
